UNITED STATES PATENT OFFICE.

AMOS H. SMITH, OF NEW YORK, N. Y., ASSIGNOR TO AMERICAN BANK NOTE COMPANY,
A CORPORATION OF NEW YORK.

NUMBERING-MACHINE.

1,240,893.

Specification of Letters Patent. Patented Sept. 25, 1917.

Application filed October 23, 1914. Serial No. 868,301.

To all whom it may concern:

Be it known that I, AMOS H. SMITH, a citizen of the United States, residing at the borough of Bronx, city of New York, county 5 of Bronx, and State of New York, have invented certain new and useful Improvements in Numbering-Machines, of which the following is a specification, reference being had to the accompanying drawings, which 10 form a part thereof.

My invention relates to numbering machines and more particularly to a type thereof adapted to print numbers upon sheets, and to be power-driven.

15 In numbering printed sheets of paper, especially those having bank notes printed thereon, it is necessary to print corresponding numbers upon both sides of the printed sheet. Heretofore with bank notes as well 20 as other kinds of work, it has been customary to number only one side of the sheet at a time. By my invention, I provide a machine capable of printing numbers upon both 25 sides of a sheet of paper at a single run of the sheet through the machine, the machine being 30 so constructed that the operation of the elements of each couple will be accurately timed as to each other, and succeeding couples will be so driven as to facilitate the reversal of the sheet and insure substantial 35 equality in the speed of the different couples in order to secure continuity in the operation of the machine.

While in a machine made in accordance 35 with my invention, one of the platen cylinders, in addition to coöperating with its numbering head element, performs the function of a collecting or delivery cylinder and a reversing cylinder, I so construct the machine 40 that the printing couple, of which this impression cylinder is a member, may be rendered inoperative for printing purposes without, however, affecting the other operative effects of said impression cylinder. In 45 order to insure the proper laying of a sheet of paper upon the second impression cylinder, when transferring a sheet thereto from the first cylinder, and during the reversal of the paper, I provide means whereby said 50 cylinders will be always driven at a uniform peripheral speed, while affording that slight play between the gears upon each impression cylinder and upon the numbering head element coöperating therewith necessary by

reason of those slight fluctuations in the 55 speed of the printing element and the impression element of a printing couple due to variances in the diameters of these elements by reason of wear upon or variances in the thickness of the blankets used upon the impression cylinder. I also provide conveniently accessible means whereby when the power is cut off, the movement of the parts under momentum, may be arrested to prevent loss in the progression of the numbers 60 through the actuation of the numbering heads when no sheet has been fed to the machine. I also provide means whereby the printing elements of each couple may be independently adjusted circumferentially, to 65 insure accuracy in the positioning of the numbers upon each face of the printed sheet.

My invention consists primarily in a numbering machine embodying therein two successively operative drums each adapted to 75 carry a printing surface or printing surfaces, two successively operative impression cylinders each coöperating with the printing surface or surfaces upon a drum, means whereby a sheet is transferred from one cylinder to the other and is reversed while being transferred, means adapted to receive each printed sheet upon its delivery from the second of said cylinders, and means whereby power is applied to said impression 80 cylinders, and through said impression cylinders, to their associated drums respectively; and in such other novel features of construction and combination of parts as are 85 hereinafter set forth and described and more 90 particularly pointed out in the claims here-to appended.

Referring to the drawings:—

Figure 1 is a side elevation of a numbering machine embodying my invention, 95 portions of the said frame being broken away;

Fig. 2 is an end view thereof;

Fig. 3 is a diagrammatic showing of the machine;

Fig. 4 is a detail view of the supporting and shifting mechanism of the second numbering drum; and

Fig. 5 is a detail view of the gripper mechanism by means of which a sheet is 105 transferred from one impression cylinder to the other except as to the actuating mechanism for the fingers.

Like letters refer to like parts throughout the several views.

In the accompanying drawings, I have indicated the side frames of the machine by 5 the numerals 1 and 2, said side frames carrying all of the operative parts of the machine.

Mounted between said frames are two printing couples with their appurtenances, 10 the first of which is adapted to number one side of a sheet of paper and the other of which is adapted to number the other side thereof. These printing couples are so associated that they not only will be driven in 15 synchronism, but will, when the sheet in process is passing from one printing couple to the other, reverse the sheet so as to bring the desired face thereof toward the printing element of the succeeding printing couple.

The printing couple first operative upon the sheet comprises an ordinary numbering drum 3 adapted to receive a numbering head, or numbering heads, in the usual manner; and associated therewith is an inking mechanism 4; and an impact supporting rod 5 adapted for use when it is desired to turn each digit wheel of the numbering head more than once during each rotation of the drum 25 3. Said couple also includes therein the impression cylinder 6.

Adjacent this printing couple is an ordinary feed shelf 7 from which the sheets are fed thereto. The second couple comprises 35 the numbering head drum 8 with its inking mechanism 9 and impact supporting rod 10, and an impression roller 11 arranged adjacent the impression roller 6, but spaced away therefrom sufficiently to avoid any pressure 40 upon the paper when transferring from one impression roller to the other.

The numbering drums or printing elements of each couple are so arranged as to afford a sufficient interval of time before the 45 reversing of the sheet, or the delivery thereof to prevent off-setting or smudging of the imprint by reason of contact with the impression cylinder 11 or the collecting mechanism.

Associated with the impression cylinder 50 11 is a collecting or delivery mechanism, the purpose of which is to not only remove the numbered sheets from the machine, but to make it impossible for a sheet, through adhesion to the cylinder 11, to be carried upon said cylinder during more than one rotation thereof. As to the delivery of the sheet 55 from the first printing couple, the impression cylinder 11 forms a part of the delivery mechanism, and is operated at all times 60 whether the numbers are being printed upon one or both sides of the machine.

The delivery mechanism comprises a plurality of tapes 12 passed about the cylinder 65 11 and about the rollers 13, the upper reach

of said tapes passing over the guide 14 and the lower reach, over the presser rollers 15, which are in contact with the impression cylinder 11. Carried by the frame of the machine and extending into close juxtaposition to the surface of the roller 15 is the plate 16 adapted to guide the movement of the paper as it leaves the said roller.

Each of the impression cylinders 6 and 11 is provided with a gripper mechanism, 75 the fingers of which are operated in the usual manner to open and close same for receiving the sheet and for opening same to permit the delivery of the sheet. This mechanism, however, differs from the ordinary gripper 80 mechanism in that it is necessary to provide a special structure to facilitate the transfer of the sheet from the surface of one impression cylinder to the surface of the other impression cylinder, which at the time 85 is moving in the same direction. To secure this result, I provide each cylinder with a plurality of fixed gripper fingers having a reduced area against which the gripper fingers are adapted to press, both impression 90 cylinders being provided with clearance along the surface thereof adjacent said fingers. By staggering the fixed gripper fingers and fingers upon the cylinder 6 with relation to those upon the cylinder 11, and 95 simultaneously opening the fingers, said fingers, when the fixed gripper fingers of one cylinder are in alignment with the fixed gripper fingers upon the other cylinder, will overlap each other and the paper will be permitted to drop from the fixed gripper fingers upon one cylinder to the fixed gripper fingers upon the other cylinder, where they will be engaged by the gripper fingers upon the last named cylinder. The gripper fingers upon the cylinder 6 are indicated by the reference numeral 17, the coöperating fixed gripper fingers by 18 and the gripper fingers upon the cylinder 11 by the numeral 19 and the coöperating fixed gripper fingers by the numeral 20. It will be observed that by this construction, the transfer of the sheet from the cylinder 6 to the cylinder 11 may be readily effected and that the fingers 17, 100 will not interfere in any way with the transfer of the sheet because of the fact that after the transfer is effected and before said fingers are closed again the movement of the cylinders will have brought said fingers to a position where they could not engage the 105 forward edge of said sheet. The mechanism for opening and closing the fingers 17 and 19 is not illustrated in the drawings because such is well known in the art and is immaterial to this invention.

The manner of effecting the transfer of a sheet from the cylinder 6 to the cylinder 11 makes it essential that there shall be substantially no play or lost motion in the mechanism through which these gears are 110

driven, in order to insure absolute synchronism in the rotary movement of both cylinders. At the same time, it may be necessary to provide for slight play in the gear connection between each impression cylinder and its printing cylinder and to permit adjustment of the printing cylinder toward and from the impression cylinder to compensate for the unavoidable variances in the 10 diameters of these two cylinders. Any difference in the peripheral velocities of the cylinders 6 and 11 would have the effect of disturbing the position of the sheet upon the cylinder 6 and as the forward edge of the 15 sheet may be transferred during a period when other portions of the sheet are being printed, it is apparent that any feeding movement of the sheet must be avoided.

I secure the desired result by a particular 20 form of driving mechanism which I will now describe. At 21 I have shown the main power shaft of the machine carrying the gear 22 of large diameter and deriving power from the pinion 23 which in turn may 25 be driven from any source of power as an electric motor. Carried upon the shaft 21 is a small gear 24 in mesh with a large gear 25 carried by the shaft 26 of the cylinder 11. In mesh with the gear 25 is a similar 30 gear 27 carried by the shaft 28 of the cylinder 6. The gears 25 and 27 are so made as to have slight play, the main function of these gears being to impart the desired rotary movement to the number head drums 35 3 and 8 through the gears 29 and 30 carried by said drums respectively. While the gears 25, 27, 29 and 30 form a complete train, the desired accuracy in the rotary movement of the cylinders 6 and 11 is secured by a pair 40 of intermeshing gears 31 and 32 carried by the shafts 26 and 28, these gears being of slightly larger diameter than the gears 25 and 27 and so fitted as to insure substantial 45 accuracy in the drive in the two cylinders 6 and 11. Hence, the actual timing of the rotation of these cylinders is not dependent upon the gears 25 and 27, although the power used in rotating said gears is transmitted through the former.

To facilitate accuracy in the positioning 50 of the various numbers upon the sheet to be printed as to either, or both, sides thereof, I so mount the drums 3 and 8 with relation to their driving mechanism, the gears 55 29 and 30, that said drums may be adjusted circumferentially independently of movement of said gears. This adjustment preferably consists of segmental slots 33 in the gear 29 and segmental slots 34 in the gear 60 30 through which slots respectively project bolts 35, which serve to hold the drum and gear in any adjusted position.

This construction permits either drum 3 or 65 8 to be adjusted independently of the other and this adjustment is secured without

disturbing the relation of the gear train. Furthermore, it will allow irregular and minute adjustment of either drum.

The drum 8 and its appurtenances, including the gear 30, are mounted upon a 70 carriage 37 and slideable in ways 38 toward and away from the impression cylinder 11. Carried by the frame of the machine is a lever system, comprising the link 39 and the bell crank 40, by means of which said 75 carriage 37 may be moved toward or away from the said cylinder 11. Said carriage is provided with the bolts 41 and 42 so that when it is in operative position with the gear 30 in mesh with the gear 25, it may be 80 clamped to place and thus avoid a loss of this relation which might result in the absence of, or a light, imprint during the run of the machine. By this construction when it is desired to number only one side of a 85 sheet, the number drum 8 may be made inoperative without, however, affecting the operative effect of the cylinder 11 or other parts of the machine. Hence the machine may be used to print upon either or both 90 sides of a sheet as desired.

In numbering machines all of the numbering heads are actuated one or more times with each rotation of the drum, so that it is desirable to provide means whereby the 95 rotation of said drums may be quickly checked when through accident, or otherwise, no sheet has been fed to the machine. In the form of the invention shown, I mount upon the shaft 21 a brake wheel 43 100 adapted to be engaged by a brake shoe 44 upon the foot lever 45 mounted upon the side frame when adjacent said wheel. The brake shoe 44 is sufficiently heavy to drop by gravity away from the wheel 43, the pin 105 45^a serving to arrest movement of said brake shoe when it is released from said wheel. The said brake shoe is pivoted upon the lever 45 in a position conveniently accessible to the foot of the feeder.

The operation of the herein described machine is substantially as follows:—

When it is desired to number both sides of a printed sheet, the carriage 37 is brought up against the upper part of the main 115 frame of the machine as shown in Fig. 1, and clamped in this position by means of the bolts 41 and 42.

Each of the drums 3 and 8 has mounted thereon in the desired relation to each other a plurality of numbering heads. If it be found that the numbering heads upon either drum are not so located as to cause the numbers to appear in the proper places upon a printed sheet, the bolts 35 are loosened and the drums are turned slightly in either direction with relation to their gears 29 and 30 until the proper adjustment of the numbering heads is secured. Nicety in this adjustment is necessary in high class work,

such as bank notes, as precision is essential to such work.

When the machine has been properly set, the individual sheets are fed from the shelf 5 7 by hand or in any desired manner toward the impression cylinder 6, the forward edge of each sheet being grasped by the gripper fingers 17 upon said impression cylinder and held by said fingers against the platens 19.

10 While it is practically impossible to secure absolute equality in the peripheral speeds of the numbering head drums and of the impression cylinders those slight variations present during the running of the machine, will be compensated for by the loose mesh between the gears 27 and 29, thus permitting the drum 3 and cylinder 6 to be rotated in part by said gears and in part by the frictional engagement of the numbering 15 heads and the impression surface of said cylinders.

As the gripper fingers 17 approach the upper vertical radius of the impression cylinder 11, said fingers will be raised out of contact with the fingers 18 and dropped in advance of and between the fingers 20 upon the impression cylinder 11. The gripper fingers 19 upon the impression cylinder 11 will have been substantially simultaneously 25 raised so that a clear field is afforded for the forward edge of the sheet of paper to drop from its engagement with the fingers 18 upon the fingers 20 against which it will be almost instantly clamped by the descent of the fingers 19. It will be observed that at 30 this point when the upper vertical radius of the cylinder 11 is in substantial alinement with the lower vertical radius of the cylinder 6, the fingers 18 and 20 are in substantial alinement, although spaced apart sufficiently to afford clearance therebetween. Furthermore, the fingers 18 and 20 of the cylinders 6 and 11 are moving in the same direction and at the same peripheral velocity. As a result of this condition the gripper fingers 17 will not interfere with the transfer of the sheet from the cylinder 6 to the cylinder 11 and there will be no stress upon the paper sheet which could result in 40 a movement of said sheet in excess of the peripheral speed of the cylinder 6. The clearance about the fingers 18 and 20 will permit the unobstructed movement of the fingers 17 and 19 and the divergence in the 45 curved path of movement of these fingers after the transfer of the sheet has been effected, will obviate any possibility of the fingers 17 interfering with the sheet after it has once been transferred.

50 It will be observed that the relation of the cylinders 6 and 11 is such that the act of transferring a sheet from the former to the latter will bring the numbered face thereon, or the outer face when upon the cylinder 6, toward the cylinder 11, and the re-

verse side thereof outwardly so as to present it to the numbering heads upon the drum 8. In this manner the sheet is not only automatically and successively fed from one printing couple to the other, but the reversal and transfer of the sheet to the other is accomplished simultaneously by a direct transfer of the sheet from one impression cylinder to the other without the aid of any interposed mechanism.

70 The impression cylinder 11 not only performs its functions of an impression cylinder, but also forms a part of a delivery mechanism by means of which the sheets of paper are carried from the cylinder 6 80 and delivered from the machine. The tapes 12 passing about the cylinder 11 over the rollers 15 and about the rollers 13 serve to both strip the printed sheets from the cylinder 11 and deliver them to the roller 15 85 by which they are dropped upon the collecting plate or shelf 16.

90 If it be desired to number only one side of a sheet, the carriage 37 may be moved by means of the link 39 and bell crank lever 40 95 away from the impression cylinder 11 sufficiently to prevent the making of an impression by the printing elements upon the drum or cylinder 8, this adjustment of the mechanism having absolutely no operative effect 100 upon any other part of the machine than the said printing element 8. The impression cylinder 11 will operate in substantially the same manner whether or not an impression is being made upon the reverse side of the sheet carried thereby.

105 It is to be observed that while the teeth of the gears 25 and 27 must be so formed as to mesh loosely with each other and with the gears 29 and 30, the gears 31 and 32 carried by the shafts 26 and 28 are in close mesh so that the cylinders 6 and 11 will always have the same speed and the gripper mechanisms of these two cylinders will always come to the same operative relation at 110 the interval when the sheet is to be transferred from one cylinder to the other. Slight fluctuations in the speeds of these cylinders would result in inaccuracy in the transferring of the sheets with a corresponding inaccuracy in the positioning of the numbers upon succeeding sheets, and momentary fluctuations in the speeds of these two cylinders might have the effect of feeding or buckling the paper while upon, and independently of the movement of, the cylinder 6.

115 A machine made in accordance with my invention is not limited to printing elements carrying numbers, as key marks or safety 120 designs of various kinds are frequently used in lieu of numbers.

125 In case a sheet of paper is not fed each time the machine turns over, every numbering head upon both drums 3 and 8 would be 130

advanced without producing sheets bearing the desired numbers. To avoid this condition, if possible, I provide the wheel brake mechanism 43, 44 and 45 so that after the power has been shut off, the running of the machine under momentum may be checked.

While in the accompanying drawings, I have shown the impression cylinder 8 as being positioned directly above the impression cylinder 11, this arrangement is not essential, it being merely necessary that one impression cylinder shall be positioned adjacent the other with that slight clearance between the surfaces thereof to avoid any possibility of the paper being pressed between these rollers. This arrangement insures the movement of the sheet, during the transfer operation, under the control of the gripper mechanism alone, thus eliminating all necessity for providing against variances in the diameters of the two impression cylinders. Substantial uniformity in the speed of rotation of the gripper mechanisms may be mechanically secured, but the diameters of the impression surfaces of the cylinders cannot be controlled with accuracy and is subject to gradual change from wear, pressure and other causes.

Throughout this specification where I have referred to a printing element, I have had in contemplation that member of a printing couple adapted to receive the actual printing surfaces.

While I have shown a mechanism wherein the sheets are fed by hand, it is apparent that any desired form of feed or feeding mechanism may be provided for without departing from the invention.

It is not my intention to limit the invention to the precise details of construction shown in the accompanying drawings, it being apparent that such may be varied without departing from the spirit and scope of the invention.

Having described the invention what I claim as new and desire to have protected by Letters Patent is:

1. A numbering machine embodying therein two successively operative drums each adapted to carrying a printing surface or printing surfaces, two successively operative impression cylinders each coöperating with the printing surface or surfaces upon a drum, means whereby a sheet is transferred from one cylinder to the other and is reversed while being so transferred, means adapted to receive each printed sheet upon its delivery from the second of said cylinders, means whereby both of said impression cylinders are rotated at uniform speed, and coöperating means carried by

said cylinders respectively and said drums having slight lost motion therein whereby variances in the diameters of said cylinders and said drums will be compensated for and 65 said drums will be driven from said cylinders.

2. A numbering machine embodying therein two successively operative drums each adapted to carry a printing surface or 70 printing surfaces, two successively operative impression cylinders each coöperating with the printing surface or surfaces upon a drum, means whereby a sheet is transferred from one cylinder to the other and is reversed while being so transferred, means adapted to receive each printed sheet upon its delivery from the second of said cylinders, close meshing gears rotatable with said cylinders, and coöperating loose mesh gears 80 carried by said cylinders respectively and said drums respectively whereby slight lost motion is afforded between the coöperating gears upon each cylinder and each drum to compensate for variances in the diameters 85 of said cylinders and said drums respectively.

3. A numbering machine embodying therein two successively operative drums each adapted to carry a printing surface or 90 printing surfaces, two successively operative impression cylinders each coöperating with the printing surface or surfaces upon a drum, means whereby a sheet is transferred from one cylinder to the other and is reversed while being so transferred, means adapted to receive each printed sheet upon its delivery from the second of said cylinders, close meshing gears rotatable with said cylinders, coöperating loose mesh gears carried by said cylinders respectively and said drums respectively whereby slight lost motion is afforded between the coöperating gears upon each cylinder and each drum to compensate for variances in the diameters 95 of said cylinders and said drums respectively, each of said gears carried by said drums having a segmental slot therein and means carried by said drums respectively and moving in said slot whereby said drums 100 may be adjusted circumferentially in relation to said gears and may be locked in their adjusted position.

In witness whereof I hereunto affix my signature in the presence of two subscribing witnesses, this 22nd day of October, 1914.

AMOS H. SMITH.

Witnesses:
